STAKING MACHINE

David Edgar, Lynn, Mass., assignor to The
Tanning Process Company, Boston, Mass., a
corporation of Massachusetts

Application April 7, 1938, Serial No. 200,703

17 Claims. (Cl. 149—16)

This invention relates to machines for treating hides and skins. While the invention is illustrated as embodied in a machine for staking certain classes of skins as, for example, relatively light skins in the "crust," and for staking and blocking skins which have been tanned and treated to produce a suede surface thereon, it will be understood that the invention and various important features thereof may have other applications and uses.

In leather manufacturing operations, tanners perform staking operations upon skins usually with the aid of well-known types of stakers wherein reciprocating staking tools operate upon successive portions of each skin, the operation of staking the skin requiring much time and effort on the part of the operator, due to the fact that the path of the tool upon the work is relatively narrow and each path must overlap each preceding path to insure that all portions of the work are adequately treated. It has heretofore been proposed to perform staking operations by a multiplicity of staking tools mounted either on endless belts or on the surface of a cylinder of substantial diameter. In these prior constructions, it is probable that too many blades were provided for simultaneous operation on a given skin or that blades on co-operating rolls or cylinders were arranged for an interlocking effect that could not be properly adjusted. Apparently the skins were subjected in these machines to so great a staking pressure as to result in an inferior product and in some cases an unmarketable product due to damaged grain surfaces. However, to the best of my knowledge and belief, no machines of the latter type are actually in use in manufacturing operations in this or any other country, in spite of what appear to be obvious advantages, such as increased capacity of the machine and safety for the operator, particularly in comparison with the well-known reciprocating staking head of the type shown in United States Letters Patent No. 604,560, granted May 24, 1898, on an application filed in the names of Craig and Slocomb.

It is an object of this invention to provide a staking machine of the multiple blade type designed to present a tool surface extensive enough to extend across the full width or length of each of the skins of the class for which the machine is designed, thus providing for a speeding up of staking operations. It is a further object of the invention to provide a staking machine of the multiple blade type which will operate efficiently

so that there is no sacrifice of quality accompanying the increased capacity of the machine.

It is an important feature of the invention that a work support is provided which has a work supporting surface layer yielding throughout for pressing successive portions of a skin against staking blades on a carrier member moving at relatively high speed. Because of the yielding nature of all portions of the work supporting surface layer, the blades press successive portions of the skin relatively deeply into said surface layer whereby the said portions are sharply bent, under yielding pressure, over the edges of the rapidly moving staking blades. Hence staking of the skin is accomplished simultaneously over large areas of the latter without danger of injury to the skin. By this arrangement of blades in combination with a uniformly yieldable work supporting surface layer, the staking operation is accomplished rapidly and at the same time efficiently. To effect treatment of different classes of work, as for instance, relatively heavy skins as well as light sheep or kid skins, it is necessary only to substitute a yielding surface of greater or lesser firmness or resistance to the action of the blades in forcing portions of the leather into said yielding surface.

Another important feature of the invention resides in the provision of a plurality of friction members, arranged in alternation with the staking blades, against which portions of each skin undergoing treatment may be pressed to draw adjacent portions of the same skin over the edges of the staking blades with the desired tension on the skin, the arrangement being further such that the skin is yieldingly pressed against both the blades and the described members, the latter having the effect of increasing the staking pressure by providing the necessary tension on the skin without danger of injury to the latter.

Conveniently, the staking blades are arranged helically on the surface of a cylinder in such manner as to extend in opposite directions from the longitudinally median portion of the cylinder and the friction members referred to are in the form of ribs of felt or other suitable material arranged in alternation with the blades so that, during rotation of the cylinder, the skin is stretched in a direction longitudinally of the cylinder and at the same time is operated upon to stretch and soften successive portions of the skin until its whole surface is treated.

As illustrated, a work supporting surface layer yielding throughout is provided by a brush roll having bristles suited to press skins of a given

firmness and weight over the edges of the blades and into contact with the surfaces on the ribs which alternate with the blades.

- The illustrated machine is particularly useful 5 in staking operations upon suede skins since the surfaces of the ribs not only aid in the staking operation but, because of their frictional quality, serve to smooth out the nap and lift it from the surface of the skin with the fibers of the nap 10 all pointing substantially in one direction, that is, away from the backbone line of the skin. This effect on the suede surface has heretofore been obtained by a hand operation known to tanners as blocking.
- 15 Conveniently, the brush roll is mounted on swing arms arranged to be power operated in such manner that the brush roll will be caused to present a full length portion of a skin to the bladed cylinder so that substantially one-half of 20 the skin may be treated, the brush roll being then caused to move to work receiving position preparatory to introducing the untreated portion of the skin which is then treated to complete the staking operation on that skin. In a 25 preferred construction, a power driven feed roll is provided to cooperate with the brush roll in feeding the skin past the surface of the bladed cylinder while the latter operates at relatively high speed to effect the staking operations.
- 30 With these and other features and objects in view, the invention will now be described in detail in the specification and then pointed out more particularly in the appended claims.

In the drawings,

- 35 Fig. 1 is a view in end elevation of a staking machine illustrating one embodiment of the invention;
- Fig. 2 is a top plan view of the machine shown in Fig. 1;
- 40 Fig. 3 is a plan view of the middle portion of the bladed cylinder where the blades meet, it being understood that the blades are arranged on the cylindrical surface in a right and a left helix;
- Fig. 4 is a detail view of the adjacent ends of 45 two blades in oppositely extending helices;
- Fig. 5 is a somewhat diagrammatic sectional view through the work treating portions of the machine; and
- Fig. 6 is a sectional view along line VI—VI of 50 Fig. 2.

In the illustrated machine, which is specially designed to perform staking operations upon skins in the "crust" and also staking and blocking operations upon tanned skins of the type 55 known as suede, there is provided a yielding work supporting surface in the form of a brush roll 10 adapted to press successive portions of a skin 11 against helically arranged blades 12 on a cylinder 14 of relatively large diameter. Since the 60 bristles of the brush roll 10 are yielding and since the brush roll is of about the same diameter as the bladed cylinder 14, the blades 12 will press contacted skin portions of substantial size rather deeply into the surface of the brush roll, 65 whereby successive portions of the skin are bent rather sharply over the edges of the blades to effect a staking operation of the skin, that is, a stretching and softening of the skin 11. Since the brush roll is a true cylinder, its surface layer 70 of resilient yielding material presents a substantially even cylindrical surface for engagement with the skin, whereby the pressure of staking operations is the same on all parts of the skin. It is to be understood that, for light skins, the 75 bristles on the brush roll 10 are relatively long

and flexible, while for operations on heavier skins the bristles are heavier, shorter, and much less flexible. It is clear that the brush roll 10 constitutes an even-surfaced work support having a 5 surface layer which is substantially uniformly yielding throughout, so that no matter where a blade 12 may press upon the work support and upon the skin undergoing treatment the contacted portions of the latter will be pressed into the yielding surface of the work support thereby 10 bending the skin rather sharply over the blade to effect a staking operation on the skin.

As shown, there are secured to the cylinder 14, 15 between adjacent blades 12, a plurality of ribs 16 which present each a relatively broad surface as 20 compared to the blades. It is to be understood that the number of ribs between the blades may be varied. These ribs 16 are made of material which is relatively firm, although somewhat compressible, and which at the same time will act because of its frictional quality to retard movement 25 of the skin surface 11 over the surface of the rib, thereby increasing locally the tension on the skin and thus co-operating with the blades in a staking and stretching operation when only staking is desired as, for instance, in operating on skins 11 in the "crust," it being understood in this connection that skins in the "crust" are skins which have been tanned and/or colored and subsequently dried. Preferably the ribs 16 are 30 made of rather firm felt in which case the surfaces of the ribs, because of the frictional quality of their relatively broad surfaces, not only co-operate with the blades in staking the skins 11 35 but also, in the case of suede tanned skins, serve to smooth out and lift the nap of the suede surface. As clearly shown in Figs. 2 and 3, the ribs of felt are arranged helically between the helically arranged blades and extend in opposite directions from a longitudinally middle part of the 40 bladed cylinder.

In order that the operator may exercise a certain amount of control of the skin 11 undergoing treatment, the brush roll 10 is idly mounted in 45 swing arms 18, respectively carried by stub shafts 20 mounted in the frame of the machine. However, to assist the operator in moving the skin past the bladed cylinder 14, there is provided a feed roll 22 rotatably mounted in the frame of the machine and power driven at a predetermined 50 speed, as will hereinafter be described. The feed roll is driven in a direction the reverse of the bladed cylinder 14 to assist the operator in moving the work piece out of the machine, the work supporting surface of the brush roll 10 moving 55 away from the bladed cylinder 14. It will be understood that the feed roll 22 not only helps to feed the skin in co-operation with the brush roll 10 but that it serves also to aid in keeping the skin 11 under tension while it is being treated 60 with the blades 12 and ribs 16. Because of the yielding nature of the brush roll 10, the operator retains a substantial control of the feeding speed of the skin and of the amount of tension 65 at which the staking operation is performed, since he may regulate these effects to a large extent by the force of the pull that he exerts upon that portion 24 (Fig. 5) of the skin 11 which is within his grasp. The brush roll 10 may properly be described as slow-moving, since it is moved by 70 and moves with the skin.

Upon reference particularly to Fig. 5, it will be observed that a blade 12 presses the contacted portion of the skin rather deeply into the yielding surface of the brush roll 10 whereby the skin 75

is bent rather sharply over the edge of the blade and that adjacent portions of the skin are pressed against the surfaces of the closely adjacent ribs 16 (Fig. 6) whereby stretching and softening operations are effected with respect to successive portions of the skin. It is to be remembered in this connection that the cylinder with its blades 12 and ribs 16 is rotating at about 750 R. P. M., while the brush roll 10 with its yielding surface is moving at a very much lower rate, of the order of 20 R. P. M., so that the skin is moved past the rapidly operating blades and ribs at a rate of only about 50 feet per minute. It follows that the blades and ribs repeatedly treat highly localized adjacent areas of the skin in succession during the travel of the skin. This is one of the reasons that the machine is successful in softening and stretching the skin.

Moreover, the surfaces of the felt ribs act repeatedly to smooth the nap on a suede skin constantly in a given direction whereby the said nap is laid down smoothly while at the same time it is lifted somewhat from a condition where it appeared to be pasted down as a result of the slicking operation which preceded drying of the skin. In other words, the nap fibers appeared to be more or less adherent to the skin surface and to each other whereas, by the blocking action of the ribs, the nap is lifted somewhat with the fibers lifted and separated from each other to provide a soft and uniform velvety appearance.

As indicated in the foregoing description, the brush roll 10 is mounted for movement between work receiving and work presenting positions with respect to the bladed cylinder 14. Power means is preferably provided for moving the brush roll from one of its positions to the other at the will of the operator. Conveniently, a pair of connecting rods 30 (Figs. 1 and 2) are pivotally mounted on the ends of a shaft 32 which carries the brush roll 10, the other ends of the connecting rods 30 being pivotally connected to cranks 34 on a crank shaft 36 adapted to be clutched for one-half a revolution to a driven shaft 38. Upon stepping on a treadle 40 (Fig. 1), the crank shaft is clutched to the shaft 38 so that the brush roll 10 moves from its open or work receiving position in Fig. 1 to its closed position shown in full lines in Fig. 5. The brush is held unyieldingly in that position until the operator again depresses the treadle 40 whereupon the crank shaft is turned through another half revolution to move the brush roll to open position shown in Fig. 1. This is accomplished through the operation of a clutch and stop device which may be of the type disclosed in Figs. 1, 2, 6 and 7 of the drawings in United States Letters Patent No. 873,790, granted December 17, 1907, upon application of Reed and Perkins. Preferably, the clutch (not shown) is of a type wherein provision is made for preventing repetition of the clutching operation even if the treadle be held down.

Power means is provided also for rotating the bladed cylinder 14, said means comprising a pulley 44 (Fig. 1) on the armature shaft of a motor 46, a suitable belt 48 passing around the pulley 44 and also around a pulley 50 secured to a shaft 52 to which the cylinder 14 is secured, thus making provision for rotation of the cylinder at high speed. Secured to the pulley 50 or (as shown) integral therewith is a second pulley 53 about which passes a belt 54 which also passes around a pulley 56 secured to the shaft 38. This shaft 38 has secured thereto a pinion 58 arranged to

be in mesh with a gear 62 which is adapted to be clutched to the crank shaft 36 by a clutch and stop device, preferably of the type referred to above.

Conveniently the shaft 38 carries a sprocket wheel 70 (Fig. 2) about which passes a sprocket chain 72 which also passes about a sprocket 74 secured to a shaft 76 having at its other end a pinion 78 arranged to be constantly in mesh with another pinion 80 secured to a shaft 82 upon which the feed roll 22 is mounted. As heretofore stated, the bladed cylinder 14 is driven at high speed, while the feed roll 22 is driven at a much lower speed, whereby successive portions of the work piece are repeatedly operated upon by the high speed bladed cylinder.

There is preferably provided a dust removal means particularly useful when suede skins are being treated, comprising a conduit 90 the upper end of which is open in close juxtaposition to the revolving surface of the cylinder 14. The lower end of the conduit 90 is connected to a pipe 92 which leads to a chamber wherein there is located a blower (not shown). Conveniently, the upper front wall of the conduit 90 ends in a curved metal roll 100 to serve as a guide to keep the skin 11 from moving toward the open end of the conduit 90. If desired, a further guide 102 may be provided in the form of a metal sheet member extending forwardly under the brush roll 10 in a position to guide the skin downwardly and toward the front wall of the conduit 90, so that when the roll 10 is in work presenting position the skin 11 will hang substantially vertically between guide members 100 and 102.

In operating the machine shown in the drawings, a skin is placed over the brush roll 10 when the latter is in the open position shown in Fig. 1. Upon depressing the treadle 40, the brush roll 10 is caused to move to the work presenting position shown in Fig. 5, where it remains until the operator again depresses the treadle. During the time that the brush roll is in work presenting position, the cylinder 14, in its high speed rotation, causes the blades 12 and the ribs 16 to treat successive portions of the skin repeatedly while the latter is presented by the yielding surface on the slowly moving brush roll 10. Each blade 12 on the cylinder 14 presses a portion of the skin rather deeply into the yielding surface of the brush roll whereby the skin is drawn sharply over the staking edge of the blade. The ribs 16 also aid in the staking operation since they operate to increase the staking pressure and tend to soften the skin through frictional contact therewith against the pressure of the brush roll. In case a suede skin is being treated, the frictional surfaces on the ribs 16 also serve to smooth out and lift the nap on such suede surface to impart a velvety feel to the leather. Since the brush roll 10 is idly mounted, the operator controls, to a substantial extent, the feeding of the skin past the bladed cylinder 14, the feed roll 22 assisting in the feeding of the skin toward the operator. Substantially one-half of the skin is introduced for the first treatment, since it is desirable to have the staking take place in a direction away from the backbone line of the skin toward the margins thereof in the flanks and belly portions of the skin. Subsequently the skin is reintroduced with the then untreated half in position to be treated, the operator securing the desired movements of the roll 10 through his control of the treadle 40.

Having described my invention, what I claim

as new and desire to secure by Letters Patent of the United States is:

1. In a staking machine, a cylinder having a plurality of blades on its cylindrical surface for operating on a skin, a work supporting roll having a surface layer of resilient yielding material which normally presents a substantially even surface throughout the work engaging part of the roll, the blades being operative to sink successive portions of the skin into the layer of yielding material whereby such portions are bent sharply over the edges of the blades during relative movement between the blades and the skin to effect staking of the latter, the work supporting roll being held unyieldingly in operative relation to the bladed cylinder with its surface moving at substantially the same rate as the skin, and means for rotating the bladed cylinder at high speed.

2. In a staking machine, a cylinder having a plurality of helically arranged blades on its cylindrical surface for operating on a skin, a work supporting roll of yielding material adapted to press a skin into engagement with the surface of said cylinder, said work supporting roll being freely rotatable and adapted to rotate with the skin passing thereabout, and means for driving said cylinder at a faster speed to provide relative rotation thereof with respect to the work support and skin thereby to effect staking of the latter.

3. In a machine for treating skins, a cylinder having a plurality of blades on its cylindrical surface for operating on a skin by relative rotation with respect thereto, said blades being positioned relatively to each other to effect spreading of the skin in opposite directions from the median line thereof extending in the direction of relative movement between the skin and the blades, and a cylindrical work support of a diameter about that of the bladed cylinder, said work support being movable with the work and having an even surface to present to the skin and also a surface layer substantially uniformly yielding throughout and operative to press portions of the skin sharply over the edges of the blades during the said relative movement between the blades and the skin to effect staking of the latter.

4. In a machine for staking skins, a cylinder having a plurality of blades on its cylindrical surface for operating on a skin, said blades being positioned relatively to each other to effect spreading of the skin in opposite directions from the median line thereof extending in the direction of relative movement between the skin and the blades, a brush roll of about the same diameter as the cylinder and having a surface layer substantially uniformly yielding throughout, the blades being operative to sink successive portions of the skin into said yielding surface layer, whereby such portions of the skin are sharply bent over the edges of the blades during relative movement between the blades and skin, and treadle controlled means for supporting the brush roll for free rotation therein and for moving said brush roll between work receiving and work presenting positions with respect to the bladed cylinder.

5. In a machine for treating skins, a plurality of blades for operating on a skin, said blades being positioned relatively to each other to effect spreading of the skin in opposite directions from the median line thereof extending in the direction of relative movement between the skin and the blades, a rotary member carrying said blades

and movable to present successive blades for treatment of a given skin, a brush roll of about the same diameter as the rotary member and arranged to support yieldingly successive portions of the skin against the thrust of blades and operative to bend such portions of the skin sharply over the edges of the blades to effect a staking operation, pivoted arms in which the brush roll is mounted for free rotation, and treadle controlled means for moving the arms to cause opening and closing of the brush roll with respect to the rotary bladed member.

6. In a staking machine for skins, a plurality of blades for operating on a skin, a plurality of ribs of relatively firm material arranged in alternation with the blades, each rib having a frictional work contacting surface relatively broad in comparison with the blades, and a roll having a surface layer of resilient yielding material which normally presents a substantially even cylindrical surface for engagement with the skin, said layer of yielding material co-operating with the blades and ribs to press portions of the skin against the frictional surfaces on the ribs whereby other portions of the same skin are bent sharply over the edges of the blades, thereby to effect staking operations on the skin during relative movement of the skin with respect to the blades and the roll.

7. A machine according to claim 6, in which a brush roll presents a uniformly yielding surface for co-operation with the blades and ribs to effect staking operations on the skin.

8. In a machine for treating skins, a plurality of blades for operating on a skin, said blades being positioned relatively to each other to effect spreading of the skin in opposite directions from the median line thereof extending in the direction of relative movement between the skin and the blades, a plurality of ribs arranged in spaced relation between the blades and substantially co-extensive therewith, each rib having a relatively broad work contacting surface in comparison with the blades, said work contacting surface of the ribs being frictional in quality and located substantially lower than the level of the edges of the blades, a member to support and move the blades and ribs, and a brush roll to press portions of a skin yieldingly against said ribs whereby other portions of the skin are bent rather sharply over the projecting edges of the blades to effect a staking operation of the skin during relative movement of the skin with respect to the ribs and blades.

9. In a machine for staking skins, a rotary work support movable with and at substantially the same speed as the work, said work support having an even surface to present to a skin and having also a surface layer substantially uniformly yielding throughout, and a rotary cylinder rotatable at a speed greater than said work support to operate on a skin while the latter is backed by the yielding work supporting surface, said work supporting surface and the operative surface of the cylinder having about the same dimensions, said cylinder having helically arranged blades on its cylindrical surface extending in opposite directions from a longitudinally median part, and said blades operating to sink portions of the skin into the yielding surface layer of the work support whereby said portions are bent sharply over the edges of the blades thereby to spread out and soften the skin undergoing treatment during rotation of the cylinder with respect to the skin.

10. A machine according to claim 9 in which the rotary work support is a brush roll.
11. A machine according to claim 9, in which ribs of relatively firm material are helically arranged in alternation to the blades and in spaced relation thereto to cooperate with said blades in staking operations on the skin.
12. In a machine for treating skins, a work support having a surface layer yielding throughout, and a rotary cylinder to operate on a skin while the latter is backed by the yielding work supporting surface, said cylinder having helically arranged blades on its cylindrical surface extending in opposite directions from a longitudinally median part, said blades serving to spread out and soften the skin undergoing treatment during rotation of the cylinder, said cylinder having also ribs of relatively firm felt of substantial thickness, so that each rib presents to the skin an effective frictional surface thereby increasing locally the staking tension on the skin, the ribs being helically arranged in spaced relation to each other and to the blades to co-operate with said blades in staking operations on the skin.
13. In a staking machine for light skins, a brush roll to serve as a yielding work support for a skin undergoing treatment, and a cylinder having helically arranged blades extending in opposite directions from a longitudinally median part of the cylinder and having also ribs of relatively firm material helically arranged between the blades, the work contacting surfaces of the ribs being substantially lower than the operative edges of the blades, whereby portions of the skin are bent sharply over the edges of the blades by the brush roll to stake the skin undergoing treatment.
14. In a machine for treating skins, a work support having a surface layer yielding throughout, a cylinder to operate on a skin while the latter is backed by the yielding work supporting surface, said cylinder having helically arranged blades on its cylindrical surface extending in opposite directions from a longitudinally median part, said blades serving to spread out and soften the skin undergoing treatment, said cylinder having also ribs of relatively firm material helically arranged in spaced relation between the blades to co-operate with said blades in increasing locally the tension of staking operations on the skin, and a driven feed roll co-operating with the yielding surface layer of the work support to feed the skin relatively to the cylinder.
15. In a machine for treating skins, a brush roll serving as a work support having a uniformly yielding surface, a cylinder to operate on a skin while the latter is backed by the yielding work supporting surface, said cylinder having helically arranged blades on its cylindrical surface extending in opposite directions from a median part, said blades serving to spread out and soften the skin undergoing treatment, and a driven feed roll arranged to co-operate with the brush roll in feeding the skin.
16. In a machine for staking and blocking suede skins, a work support having a surface layer yielding throughout, a cylinder for treating a skin presented with the suede surface toward said cylinder, helically arranged blades on the surface of the cylinder extending in opposite directions from the longitudinally median part of the cylinder, and ribs of relatively firm material helically arranged on the surface of the cylinder between said blades, the ribs each having a relatively broad work treating surface located at a level substantially below that of the edges of the blades, whereby the blades by sinking into the yielding surface of the work support operate to stretch out and soften a skin while at the same time the ribs smooth out the suede surface of the skin undergoing treatment.
17. In a machine for staking and blocking suede skins, a brush roll having a yielding surface, a cylinder for treating a skin presented with the suede surface toward said cylinder, helically arranged blades on the surface of the cylinder extending in opposite directions from the longitudinally median part of the cylinder, and ribs of felt helically arranged on the surface of the cylinder between said blades, the ribs each having a relatively broad frictional surface located at a level substantially below that of the edges of the blades, whereby the blades by sinking into the yielding surface of the brush roll operate to stretch out and soften a skin while at the same time the ribs smooth out the suede surface of the skin undergoing treatment.

DAVID EDGAR. 50
